Application July 6, 1933, Serial No. 679,150

5 Claims.

(Cl. 139—8)

This invention relates to the weaving of tuft pile fabrics of the Axminster type and is concerned more particularly with a novel method of weaving such fabrics and a new loom by which 5 this method may be practiced.

In the manufacture of tuft pile fabrics of the Axminster type, the looms now in most common use are of the tube frame type. In such looms, the yarns for the tufts are wound on spools carried on tube frames mounted in transporting chains in an order determined by the pattern. The chains are advanced by a step by step movement and, in each period of rest, one of the tube frames is removed from the chains by 10 a transfer mechanism and presented to the fabric. Each frame carries a plurality of tubes, one for each of the yarn ends on the spool, and in the operation of inserting the tuft yarns, the frames are lowered so that the tubes pass between the warp threads and the yarn ends which project from the tubes are thus placed in position to be bound by a weft shot. In the ordinary loom of this type, the holding weft shot is inserted through the warp threads and beaten up 15 while the tuft yarns project down below the warp threads and the tube frames lie slightly above the threads. The frame is then raised by the transfer mechanism so that the tuft yarns are drawn off from the spool, the ends thereof 20 which lie below the warp threads are looped about the holding weft shot by means of a comb, and the lengths of yarn inserted are then severed from the supplies. The remaining weft shots of 25 the cycle are then inserted in the usual manner, and during this time, the tube frame is restored to the chains, the chains are advanced to bring another frame in position, and at the proper instant, that frame is removed from the 30 chains by the transfer mechanism and lowered to the fabric.

In the manufacture of pile fabrics on a loom of the tube frame type, it is the customary practice to use warp threads consisting of soft cotton and a relatively stiff weft thread, for example, one made of jute. The reason for this is that unless the weft thread employed has sufficient rigidity to resist the tension of the warp threads, the weft shots will be crimped by the warp threads as the weaving proceeds, and this will result in a drawing in or shrinkage of the fabric in the direction of the weft threads. Shrinking or shortening in the width of such a fabric is a serious matter in the operation of power looms of this type because the spacing of 35 the tubes on the tube frame and of the teeth

of the comb are fixed and invariable and depend on the type of fabric being woven, being selected so that there will be a definite number of pile tufts per inch. Accordingly, when shrinking occurs, the warp threads are drawn together to an extent such that it may become impossible to pass the tubes between the warp threads to insert the pile yarn ends in the fabric. Also when the warp threads are drawn together in this manner, it may be impossible for the teeth of the comb to pass upward properly between the warp threads to complete the looping of the free ends of the inserted yarn about the holding weft shot.

The seriousness of the shrinkage above mentioned resulting from the use of weft threads of soft material will be appreciated when it is understood that in the weaving of an Axminster rug 11' 3" in width, 945 tufts are required across the rug in the line of the weft shots and when soft weft is used and it is crimped by the tension of the weft threads, the width of the fabric is reduced to approximately 10' 9" at the fell of the goods. With such a shrinkage, it will be at once evident that the mechanical means having a pitch for the insertion of 945 tufts in a space of 11' 3" cannot insert these tufts, when the space has been reduced to 10' 9".

Because of the difficulties encountered when soft weft is employed in the weaving of an Axminster fabric on a loom of the type above described, such looms heretofore have been confined to the manufacture of fabrics in which relatively stiff weft threads are used. However, there has recently been a substantial importation into this country of rugs having the face pattern visible at the back and having weft shots of the same soft material as the warp threads, these fabrics having quality, feel, and appearance superior to that of similar fabrics made with stiff weft threads of jute.

There are no looms in this country, with the possible exception of a relatively few looms of the gripper type, which can be used to produce a fabric which has a multiplicity of colors in the face and back patterns and soft weft and warp threads, and accordingly, the domestic mills have not been able to produce fabrics which can compete with the imported fabrics. The great majority of power looms in this country suitable for the production of fabrics of the Axminster type include tube frames and their associated mechanism for introducing the pile yarns and, while such looms are the only ones whose characteristics lend themselves to the possible production of fab-

rics which can compete with the imported fabrics attempts to use soft weft and warp threads in these looms as now constructed have not been successful.

5 In attempting to modify the present Axminster looms of the tube frame type in order that soft weft thread may be used, numerous expedients have been employed.

For example, the use of temples for holding out 10 the edges of the fabric and preventing shrinkage has been attempted, but this expedient did not prove satisfactory because injury was done to the pile and back surface of the fabric, and furthermore, the temples do not hold the warp 15 threads apart with a uniform spacing. Attempts have also been made to achieve the desired result by using a sized weft thread but this increases the cost of the fabric and does not produce uniform results.

20 While fabrics of the desired characteristics can be produced on looms of the Brinton type in which grippers present lengths of pile yarns to the fabric to form the tufts, these looms are expensive to install and maintain, there are only a limited number of such looms available, and the looms do not function satisfactorily, nor can they be maintained cheaply when used for the weaving of wide fabrics. Furthermore, since the majority of looms in use in this country are of the tube frame 25 type, and the mills cannot afford to discard such looms and install new equipment, it has become highly important to provide improvements which can be incorporated in looms of the tube frame insertion type so that fabrics can be woven thereon 30 in which the pattern appears on the back, the pattern designs contain a multiplicity of colors, and the weft and warp threads are both of a relatively soft material.

The present invention is accordingly directed 40 to the provision of a novel loom of the tube frame type for weaving Axminster fabrics, in which the difficulties above mentioned are overcome, the new loom being so constructed that weft material of the desired soft characteristics 45 can be employed in the fabric without causing shrinkage. The new loom also includes other features of novelty such as the elimination of all combing operations, and in this loom fabrics may be produced in which there is a full showing 50 of the face pattern on the back without the use of auxiliary moving parts, such as combs, tuft holding bars, and plates. At the same time, the loom retains the advantages of the tube frame construction and the tuft yarns are inserted by 55 mechanism which is simpler both in construction and operation than the tuft inserting means commonly used in looms of the Brinton type.

For a better understanding of the invention, 60 reference may be had to the accompanying drawings in which

Figure 1 is a view of the loom in vertical section;

Figures 2, 3, 4 and 5 are fragmentary views 65 illustrating the functioning of certain parts during the weaving operation;

Figure 6 is a fragmentary plan view showing a portion of the breastplate and reed;

Figure 7 is a sectional view showing a portion 70 of the breastplate;

Figure 8 is a view similar to Figure 6 showing a modified construction;

Figures 9, 10 and 11 are sectional views showing three types of fabric which can be produced 75 on the new loom; and

Figure 12 is a view in side elevation of a modified lay and reed construction.

Referring now to the drawings, the loom as illustrated comprises the usual side frames 20 supporting the operating parts and provided with risers 21 affording support for the girt 22. The completed fabric 23 passes under the girt and over an idler roll 24 to the spike roll 25 and then to the carpet take-up mechanism not illustrated. Attached to the risers 26 of the side 10 frames are brackets 27 which afford support for the shaft 28 carrying sprocket wheels 29 about which pass the chains 30 on which the tube frames 31 are mounted. Each of these tube frames carries one or more spools 32 on which are 15 wound the ends of tuft yarn, the ends passing from the spool through spaced tubes 33 and projecting beyond the ends of the tubes as indicated at 34. The yarns are wound on the spools and the spools are arranged on the chains in an 20 order determined by the pattern to be produced.

The transporting chains are advanced with the usual step by step motion by mechanism not shown to bring the tube frames successively above the fell of the fabric, and in each period 25 of rest, one of the tube frames is removed from the chains and presented to the fabric by transfer mechanism. This mechanism includes the usual transfer arms 35 pivotally mounted on pins 36 in arms 37 mounted on shaft 38 supported 30 in suitable brackets attached to risers 26. Arms 35 are actuated by rods 39 pivotally attached at one end to the arms by pins 40 and at the other end by pins 41 to levers 42 pivotally mounted at 43 on the loom side frames. The levers 42 are provided with rollers 44 which bear on cams 45 mounted on the loom shaft 46 which is driven by any suitable means, and the roller 44 carried by each arm is held in contact with the surface of its cam by a spring 47 attached at one end to the 40 arm and at the other end to a bracket 48 secured to the loom girt 49.

In order that the tubes of the frame to be presented to the fabric may properly enter the spaces between the warp threads as the tube 45 frame is lowered by the transfer arms, the tube frame in the arms must be tilted so that the tubes will enter the spaces at an angle. For this purpose, the clutches 50 on the ends of the transfer arms 35 and in which the tube frames are picked 50 up, are pivotally mounted on pins 51 in the arms, and attached to each clutch above the pivot pin 51 is a link 52 which is attached at its other end to an arm 53 fixed to a shaft 54 mounted in any suitable manner on the risers 26. Secured to this shaft is an arm 55 carrying a pin 56 to which is attached a link 57 also attached to one end of a lever 58. Lever 58 is pivoted on a pin 59 in an extension from an arm 42 and lever 58 carries a roller 60 which bears against 60 the surface of a cam 61 mounted on the loom shaft 46. A spring 62 attached at one end to the arm 55 and at the other end to a pin 63 on the loom side frame acts through the connections to maintain the roller 60 in contact with the surface of its cam.

The loom includes the usual mechanism, such as heddle frames 64, 65, and 66, for manipulating the warp threads to produce the desired sheds, and these heddles contain the usual heddle wires 70 or the like having eyes through which the warp threads pass. The heddles are raised and lowered to produce the desired sheds by the customary cam, linkage, and lever devices which are not shown.

The weft threads are inserted in the sheds by a needle 67 and the appropriate mechanism for advancing the needle into the sheds and withdrawing it therefrom. The needle and the needle motion may be of any well known type and, since the needle and its operating mechanism are of standard construction, they need not be further described.

The lay 68 employed in the new loom is mounted for rocking movement on a shaft 69 journaled in bearings mounted on the loom side frame and the lay carries a dent holder 70 which in turn supports the reed dents 71 in the fixed spaced relation necessary to space the warp threads in proper relation to the tubes of the tube frame. Extending downward from the lay is an arm 72 which is connected by a pin 73 to one end of a rod 74, the other end of which is pivotally connected at 75 to a lever 76. This lever is mounted on a pin 77 in a bracket 78 attached to the loom girt 46 and the lever carries a roller 79 which bears against the surface of the cam 80 mounted on the loom shaft 46. The roller is held in contact with the cam by means of a spring 81 attached to clamp 82 on the rod 74 and to a bracket 83 on the cross member 84 between the side frames. The cam 80 operates through the connections to swing the lay so that the reed dents beat up successive weft threads and the rearward travel of the lay is limited by means of a stop screw 85 supported in a bracket 86 attached to the cross member 84, this stop screw lying in the path of travel of the arm 72 and preventing further movement of the arm.

The breastplate 87 employed in the new loom is attached by brackets 88 to the cross member 22 and the breastplate is slotted at its forward edge so as to provide teeth 89. These teeth are separated by pairs of slots; one slot 90 of each pair receiving the warp threads and the other slot 91 receiving the individual dents 71 of the reed, and the teeth are spaced in accordance with the fixed spacing of the reed dents and that of the tubes 33 of the tube frames. Each tooth has an upwardly inclined face 92 for receiving a tuft yarn, this face ending in an upward projection 93. In order that the reed dents may enter the slots 91 between the teeth, the lower extremities of the pile receiving faces are beveled off, as indicated at 94 in Figure 6, so that the dents will be properly guided into the slots.

As indicated in Figure 6, the breastplate 87 has a tooth with a pile receiving face for each pile yarn loop in a transverse row of tufts in the fabric and to the rear of each of these faces, there is a slot in which a warp thread is received. The warp threads in the slots are held in proper uniform spaced relation adjacent the fell of the fabric and entirely across the fabric so that even though soft weft material is employed, of the kind that would ordinarily be crimped by the tension of the warp threads, the warp threads are prevented by the teeth from closing together and thereby interfering with the insertion of the tuft yarns. The dents of the reed also serve to hold the warp threads properly spaced and when it is desirable to insure that the warp threads will have the proper spacing from the slots in the breastplate to the heddle eyes, a second reed may be mounted in the dent holder, the dents of the second reed being shown in Figure 8 at 95. When the auxiliary reed is employed, the individual warp threads are passed in contact with opposite faces of the dents of the two reeds and the two reeds thus insure proper spacing of the

warp threads and prevent their closing in. As the warp threads are thus held properly spaced, the reed may be freely advanced and retracted in the beating up of the shot.

In the ordinary Axminster loom of the tube frame construction, the frames are dipped so that the yarn ends are passed between the warp threads directly in front of the reed and, after the completion of the dipping operations, the free ends of the yarns lie below the warp threads. After the beating up of the holding shot, the frame is raised to draw off the proper lengths of yarns from the supplies, and the inserted lengths are then severed from the frame. The ends of the yarns which lie below the warp are then turned upwardly and looped about the holding shot by means of a comb. In the loom of this invention, such a comb may be dispensed with and the tube frames may be dipped downward and away from the breastplate in such manner that the free ends of the yarns lie above the warp threads with each end of yarn positioned between the warp threads on the pile receiving face 92 of a tooth of the breastplate.

This feature of the loom is illustrated in Figures 2 to 5, inclusive, and in Figure 3, the tube frame 31 is shown as being dipped into the fabric with the yarn ends 34 lying against the faces 92 of the breastplate teeth, the free ends of the yarns lying above the warps and the yarns forming bights or loops. With the tube frame in this position, the needle 67 inserts a weft shot in the loops of the yarns, and the tube frame then rises out of the warp. The reed now advances to beat up the shot, and it forces the shot over the projections 93 on the top of the teeth of the breastplate. The tube frame is then raised further, drawing the inserted yarns tight about the shot and drawing off enough yarn from the spool to form the next tuft from this spool when it again reaches the weaving point. The tube frame is shown in this position in Figure 4. The reed is now retracted, and the tuft yarns are severed from the supplies thereof on the spool by knives 96 and 97.

The front knife 96 is mounted on a support 98 attached to arms 99 on a shaft 100 supported in a suitable bracket attached to the loom side frames and the shaft is rocked to bring the knife into cutting position by the standard mechanism for the purpose. The back knife 97 is mounted in a support 101 and slides in ways 102 in a suitable support. The back knife is also actuated by standard mechanism which need not be described.

By employing a slotted breastplate having projections on top of its teeth, it is possible to maintain the fell of the fabric in fixed position throughout the weaving and this results in a saving of tuft yarn. In an ordinary Axminster loom with a breastplate without slots, the fabric moves forward with the lay and then back and the fell of the fabric may shift a distance varying from $\frac{1}{8}$ " to $\frac{3}{8}$ ", depending on the firmness of the goods being woven, the thickness of the weft thread, and the amount of tuft yarn being inserted. When the fell of the fabric varies in this manner during the weaving, it is difficult to loop the inserted tuft yarns about the holding weft shots by a comb and similarly the knives which sever the inserted yarn from the supplies on the tube frames do not cut the same amount of yarn from the supplies in each operation because of the variation in position of the fell. As a consequence, the tufts are left in more or less

imperfect condition and in the subsequent finishing operations, substantial amounts of tuft yarn have to be removed to make an even pile surface and the amount of yarn thus removed 5 represents waste. When the slotted breastplate having the projections is employed, the fell of the fabric does not shift and the projections assist in turning up the tuft yarn around the holding weft shot. As a consequence, the severing 10 knives operate accurately and much less trimming of the pile surface is required in the finishing operations. There is, therefore, a reduction in the loss of pile yarn and the cost of production is correspondingly lowered.

15 The use of a slotted breastplate with projections in connection with tube frames dipped down and away from the breastplate to form tuft yarn loops in which the holding shot is inserted not only permits weaving fabrics with soft weft but also 20 makes it possible to make tighter tuft loops than can be produced on a gripper loom. In that form of gripper loom in which the yarns are inserted by the grippers moving down and away from the breastplate, the grippers still grip the 25 yarns while the holding shot is inserted but the yarns do not have the form of loops. When the shot is beaten up, the grippers open and release the yarns just before the shot slips off the projections, and the contact of the previously gripped 30 ends of the yarns with the projections is depended on to turn up these ends about the shot. The yarns are thus merely folded about the shot instead of being drawn tight, and frequently, a 35 yarn slips off the front face of its projection with the result that one end of the yarn remains in the fabric instead of being properly looped.

In the new loom, the inserted yarn lengths are drawn tight about the holding shot as the tube frame rises, and the inserted lengths are not severed 40 from the supplies until after the loops are completed. As the shot slips off the projections, the tension on the warp threads forces its toward the front faces of the projections, and the shot 45 clamps the yarns against those faces at the lower ends thereof. Then when the frame moves up, the yarns are drawn tight about the shot and the rear leg of each yarn loop extends up the front face of its projection and is held upright thereby until the next shot is beaten up. The fabric produced in the new loom, therefore, has tighter 50 loops and less defective loops than fabrics produced on gripper looms.

In Figures 9, 10, and 11, there are illustrated 55 three different forms of fabric which can be produced on the new loom. The fabrics shown in Figures 9 and 11 are of the three-plane, three-shot construction in which sets 103 and 104 of stuffer warp threads are used, these sets of stuffer warp threads lying in upper and lower levels. 60 The weft threads 105, 106, and 107 are inserted to lie above the upper stuffer warps, between the upper and lower stuffer warps, and below the lower stuffer warps, respectively, and the weft shots are held in place by binder warp threads 108 65 which pass over each weft shot which lies above the upper stuffer warps and below each weft shot which lies below the lower stuffer warps. The pile tuft yarns 109 are looped about weft shots which lie between the upper and lower stuffer warps. The fabric illustrated in Figure 11 is similar to that shown in Figure 9 except that the pile 70 yarns are looped around weft shots which lie below the lower stuffer warps and the pattern of the pile is thus visible at the back of the fabric.

75 The fabric shown in Figure 10 is of the two-

plane variety in which two weft shots 105 and 106 of each cycle lie above the stuffer warps 103 and 104 and weft shot 107 lies below the stuffer warps, the pile yarns 109 being looped about weft shots 107 so that the pattern is visible on the back. In 5 this fabric, there is a single set of binder warps 108 which pass over the top of the two shots lying above the stuffer warps and beneath the shot which lies below the stuffer warps. In order that 10 the operation of the loom may be clearly understood, the weaving of the fabric illustrated in Figure 10 on the new loom will be described in detail.

Referring to Figures 2 to 5, inclusive, the stuffer 15 and binder warp threads are illustrated in Figure 2 as having been manipulated by the heddles 64, 65 and 66 to form a shed for the insertion of weft 109 by needle 67, the binder warps 108 lying above the weft shot and the stuffer warps 103 and 104 below. With the warps in this position, the 20 needle enters the shed to insert a shot of weft and is then retracted. As soon as the needle has left the shed, the reed advances and the dents 71 engage the shot and beat it up, the dents entering 25 the slots between the teeth of the breastplate at the end of their forward movement and forcing the shot over the top of the projections 93 on the teeth. Two weft shots are introduced successively in the shed illustrated in Figure 2, and upon the completion of the insertion and beating 30 up of these shots, the heddles bring the warp to a level position by lowering warps 108 and raising warps 103 and 104. At this time, the transfer 35 arms have removed a tube frame from the chains, and these arms move downward until the tubes 33 of the frame have passed between the warp threads and taken the position illustrated in Figure 3. As the warp threads lie in the slots in the teeth, the threads are held apart to the desired extent and the tubes enter the group of 40 warp threads with a movement downward and away from the reed so that the portions of the 45 yarns exposed beyond the ends of the tubes rest against the faces 92 at the ends of the teeth with the extreme ends of the yarns lying above the warp threads. The heddles are now manipulated to raise warps 103 and 104 and to lower warps 108 and the needle then inserts another shot in the 50 shed thus formed. As shown in Figure 3, the portions of the pile yarns extending out of the tubes form flat loops or bights in which the weft shot is inserted through the shed.

As the needle is retracted, the tube frame is lifted out of the warp to a position in which it is clear of the reed which is then advancing, and 55 the dents of the reed enter the slots and force the weft shot over and behind the projections 93 on the teeth, as shown in Figure 4. The tuft loops then lie behind the projections 93, and while the reed is in forward position, the tube frame is 60 raised to the dotted line position shown in Figure 4 so that lengths of yarn are drawn from the supplies suitable for the next insertion of tufts from this frame. The reed now moves back and the knives 96 and 97 cooperate to sever the 65 inserted lengths of pile yarns from the supplies. Thereafter, the transfer arms return the tube frame to the chains, the chains advance the next frame into position, and the insertion of weft 70 proceeds until the next insertion of tuft yarns is to occur.

It will be noted in Figure 5 that the first weft shot of the succeeding cycle is inserted in a shed before the tuft yarns looped about the holding 75 shot of the preceding cycle have been severed.

from the supplies on the tube frame by the co-operating knives.

In Figure 12 there is illustrated a modified lay and reed construction, and in this view the arms 5 68 on shaft 69 are shown as supporting a reed base 110A. A reed base 111, which carries dents 71 arranged to enter the slots in the breastplate 67, is mounted on base 110A, and to the rear of base 111 is another reed base 112 which carries 10 dents 113 which do not enter the slots. The bases 111 and 112 are held in place by a cap 114 and bolts 115 and the bolts pass through slots in base 112. At the ends of base 110A are adjustment screws 116 bearing on the ends of base 112 15 and permitting base 112 to move relative to base 110A so as to vary the relative positions of the dents of the two reeds. The dents are preferably so positioned that they engage the warp threads on opposite sides and centre them properly relative to the slots in the breastplate.

It will be apparent, that in the new loom, the operation of the tube frames for inserting tuft yarns is in no way dependent upon the character of the weft material used, and, in this loom, soft 20 weft thread may be employed since the breastplate and the reed prevent the warp threads from closing in on one another. The new loom is much simpler than looms of the Brinton type having grippers and much cheaper to construct and 25 maintain. Also it is much more productive than the Brinton loom because it can be run at much higher speeds than are possible in a loom which includes grippers. As the features of the new loom can be incorporated at little expense in 30 many of the tube frame looms now in use, it will be apparent that the invention makes it possible to modernize old equipment and place it in shape to produce fabrics able to compete with the imported oriental fabrics and others capable of 35 production heretofore only at high cost and on expensive equipment.

I claim:

1. In a method of weaving Axminster fabrics with relatively soft weft thread on a loom of the tube frame insertion type containing a slotted breastplate having projections on top of its teeth, the steps of dipping a tube frame into the warp threads with a movement down and away from the fell of the fabric to leave the tuft yarns projecting from the tubes between the warp threads in the form of loops with the free end of each yarn adjacent the fell of the fabric and above the warp threads, forming a shed of the warp threads, inserting the holding weft shot in said shed and through said yarn loops, raising the tube frame out of contact with the warp threads, beating up the holding shot over said projections, said holding shot being then caused by the tension on the warp threads to clamp said yarns against the front faces of said projections, raising said frame further to draw off yarns from the supplies on said frame and to draw the inserted lengths of yarn tight about the holding shot, severing said inserted lengths of yarn from said supplies, and positively maintaining said warp threads laterally spaced adjacent the fell of the fabric continuously throughout the weaving operation to permit the tubes of the frame to pass between adjacent warp threads in the inserting operation.
2. In a method of weaving Axminster fabrics with relatively soft weft thread on a loom of the tube frame insertion type containing a slotted breastplate having projections on top of its teeth, the steps of dipping a tube frame into the warp threads with a movement down and away from the fell of the fabric to leave the tuft yarns projecting from the tubes between the warp threads in the form of loops with the free end of each yarn adjacent the fell of the fabric and above the warp threads, forming a shed of the warp threads, inserting the holding weft shot in said shed and through said yarn loops, raising the tube frame out of contact with the warp threads, beating up the holding shot over said projections, said holding shot being then caused by the tension on the warp threads to clamp said yarns against the front faces of said projections, raising said frame further to draw off yarns from the supplies on said frame and to draw the inserted lengths of yarn tight about the holding shot, severing said inserted lengths of yarn from said supplies, and positively maintaining said warp threads laterally spaced adjacent the fell of the fabric continuously throughout the weaving operation to permit the tubes of the frame to pass between adjacent warp threads in the inserting operation.
3. In a method of weaving Axminster fabrics with relatively soft weft thread on a loom of the tube frame insertion type containing a slotted breastplate having projections on top of its teeth, the steps of dipping a tube frame into the warp threads with a movement down and away from the fell of the fabric to leave the tuft yarns projecting from the tubes between the warp threads in the form of loops with the free end of each yarn adjacent the fell of the fabric and above the warp threads, forming a shed of the warp threads, inserting the holding weft shot in said shed and through said yarn loops, raising the tube frame out of contact with the warp threads, beating up the holding shot over said projections, said holding shot being then caused by the tension on the warp threads to clamp said yarns against the front faces of said projections, raising said frame further to draw off yarns from the supplies on said frame and to draw the inserted lengths of yarn tight about the holding shot, severing said inserted lengths of yarn from said supplies, and positively maintaining said warp threads laterally spaced continuously throughout the weaving operation both at the fell of the fabric and at a distance to the rear of the fell to permit the tubes of the frame to pass between adjacent warp threads in the inserting operation.
4. In a loom for weaving Axminster fabrics, the combination of heddle mechanism for manipulating warp threads to produce sheds, means for inserting a weft thread in each shed, a reed for beating up said weft threads, said reed having dents engaging individual warp threads from opposite sides to maintain said warp threads laterally spaced in proper relation, a breastplate having slots and projections on top of its teeth between the slots, the warp threads passing through said slots and being held laterally spaced by the walls of said slots, transporting chains, tube frames mounted on said chains, each frame carrying supplies of tuft yarns with the ends of the yarns projecting out of the tubes on said frame, transfer mechanism for removing said frames successively from the chains and dipping them into the warp threads, said mechanism operating to lower each frame and pass its tubes between the warp threads with a movement down and away from the fell of the fabric to form loops of yarn lying between the warp threads with the free ends of the yarns above the warp threads ad-

the fell of the fabric to leave the tuft yarns projecting from the tubes between the warp threads in the form of loops with the free end of each yarn adjacent the fell of the fabric and above the warp threads, forming a shed of the warp threads, inserting the holding weft shot in said shed and through said yarn loops, raising the tube frame out of contact with the warp threads, beating up the holding shot over said projections, said holding shot being then caused by the tension on the warp threads to clamp said yarns against the front faces of said projections, raising said frame further to draw off yarns from the supplies on said frame and to draw the inserted lengths of yarn tight about the holding shot, severing said inserted lengths of yarn from said supplies, and positively maintaining said warp threads laterally spaced continuously throughout the weaving operation both at the fell of the fabric and at a distance to the rear of the fell to permit the tubes of the frame to pass between adjacent warp threads in the inserting operation.

3. In a method of weaving Axminster fabrics with relatively soft weft thread on a loom of the tube frame insertion type containing a slotted breastplate having projections on top of its teeth, the steps of dipping a tube frame into the warp threads with a movement down and away from the fell of the fabric to leave the tuft yarns projecting from the tubes between the warp threads in the form of loops with the free end of each yarn adjacent the fell of the fabric and above the warp threads, forming a shed of the warp threads, inserting the holding weft shot in said shed and through said yarn loops, raising the tube frame out of contact with the warp threads, beating up the holding shot over said projections, said holding shot being then caused by the tension on the warp threads to clamp said yarns against the front faces of said projections, raising said frame further to draw off yarns from the supplies on said frame and to draw the inserted lengths of yarn tight about the holding shot, severing said inserted lengths of yarn from said supplies, and positively maintaining said warp threads laterally spaced continuously throughout the weaving operation both at the fell of the fabric and at a distance to the rear of the fell to permit the tubes of the frame to pass between adjacent warp threads in the inserting operation.

4. In a loom for weaving Axminster fabrics, the combination of heddle mechanism for manipulating warp threads to produce sheds, means for inserting a weft thread in each shed, a reed for beating up said weft threads, said reed having dents engaging individual warp threads from opposite sides to maintain said warp threads laterally spaced in proper relation, a breastplate having slots and projections on top of its teeth between the slots, the warp threads passing through said slots and being held laterally spaced by the walls of said slots, transporting chains, tube frames mounted on said chains, each frame carrying supplies of tuft yarns with the ends of the yarns projecting out of the tubes on said frame, transfer mechanism for removing said frames successively from the chains and dipping them into the warp threads, said mechanism operating to lower each frame and pass its tubes between the warp threads with a movement down and away from the fell of the fabric to form loops of yarn lying between the warp threads with the free ends of the yarns above the warp threads ad-

jacent the fell of the fabric, said mechanism raising the frame free of the warp threads to permit the reed to beat up the holding weft thread inserted in said loops of yarn and, after the beating up of said holding thread, raising the frame to draw the inserted yarns tight about the holding thread, and finally restoring the frame to the chains, and means for severing the inserted lengths of yarn from the supplies on the tube frames, said means operating on the yarns after they have been drawn tight and before the frame from which they extend has been restored to the chains.

5. In a loom for weaving Axminster fabrics, the combination of heddle mechanism for manipulating warp threads to produce sheds, means for inserting a weft thread in each shed, a reed for beating up said weft threads, said reed having dents engaging individual warp threads from opposite sides to maintain them laterally spaced in proper relation, a breastplate having slots and projections on top of its teeth between the slots, said projections having front surfaces extending substantially normal to the upper surface of the breastplate, the warp threads extending through said slots and being held laterally spaced by the

walls of the slots, transporting chains, tube frames mounted on said chains, each frame carrying supplies of tuft yarns with the ends of the yarns projecting out of the tubes of the frame, transfer mechanism for dipping the tube frames successively into the warp threads, means for operating said transfer mechanism to cause it to remove a frame from the chains, pass its tubes between adjacent warp threads with a movement down and away from the fell of the fabric to form loops of yarn lying between the warp threads with the free ends of the yarns lying about the warp threads adjacent said fell, raise the frame free of the warp threads after insertion of the holding weft shot through said loops to permit said shot to be beaten up over the projections on said breastplate, raise the frame further to draw the inserted yarns tight about said shot, said yarns being clamped by the holding shot against the front faces of said projections, and finally restore said frame to the chains after severance of the inserted lengths of yarn from said supplies, and means for severing said inserted lengths of yarn from said supplies.

WILLIAM D. KELLOGG.
